UNITED STATES PATENT OFFICE.

ADOLF BEENEKEN, OF BERLIN, GERMANY.

APPARATUS FOR OBTAINING SYNCHRONISM BETWEEN PICTURE AND MUSIC IN CINEMATOGRAPHIC PERFORMANCES.

Application filed June 3, 1924, Serial No. 717,637, and in Germany March 8, 1923.

My invention relates to improvements in apparatus for obtaining synchronism between picture and music in cinematographic performances.

5 It is known to combine cinematographic or animated picture performances in such a manner with music performances, that the picture film and a tape on which the notes are printed run off synchronously and the 10 music appropriate to the picture shown is played from the tape of music by a person or a band. The music-tape hereby passes a mark (finger). The cinematographic projecting apparatus and the driving apparatus for the music-tape are so coupled 15 together that they run in synchronism.

According to my invention the conductor of the band is able to choose the tempo in which a movement is to be performed according to his artistic perception without 20 thereby disturbing the synchronism of the music with the film even for an instant. With this end in view a mark, finger or pointer is made adjustable and at the same 25 time so connected with the drive of the projecting apparatus and the music-tape that the adjustment of the mark simultaneously controls the speed at which the projecting apparatus is driven and also the speed of 30 the synchronously running music-tape. The said mark, for instance a finger, is movable 35 in the direction in which the music is read and controls a series resistance in the circuit of the motor of the projecting apparatus in such a manner, that when it is moved

in one or the other direction more or less current is fed to the driving motor of the projecting apparatus. If, for instance the conductor of a band or the player of a 40 pianola or other mechanical musical instrument takes a movement at a quicker pace than the projecting apparatus running at the same instant at a certain speed requires the person who attends to the improved device 45 and who may preferably be seated amongst the audience notices that the note just sounded is not heard at the moment when it passes the finger or indicator. The attendant must then move the finger in such 50 a manner, that more or less resistance is con-

nected with the circuit of the driving motor and thus the projection of pictures is retarded or accelerated, so that always that note of the running music-tape which the conductor causes to be sounded moves past 55 the finger at the moment when it is sounded.

By moving the finger into one of its end positions the projector is cut out or stopped. In order to be able, however, to cut out or 60 stop the projecting apparatus or to start it again at any time instantly, an electric circuit breaker, for instance, is connected with the finger, which switches the driving motor of the projector or the projector itself out and in. 65

The music-tape contains besides the notes accurate picture indications, in such a manner that salient moments of the film are indicated at accurately corresponding places in the music-tape, by means of which the 70 readjustment of the finger may be effected if the synchronism should have been lost, even during the progress of picture performances.

For this purpose the mark or finger must 75 be adjustable independent of the throttling device, so that in this case it can have no effect upon the speed of the projector. This may, for instance, be attained by making the finger and the throttling device 80 relatively movable. For the latter purpose the finger may, for instance, be fixed upon a travelling rail provided with a rack and adapted to be moved by a pinion gearing with said rack. 85

As the part of the improved apparatus which contains the music-tape is preferably situated in the auditorium, as already mentioned, in order to enable the attendant to have a better control over the picture performance and at the same time over the music, the travelling music-tape will preferably be carried out as a negative, so that transparent notes appear on a dark background. The music-tape is hereby lit up 95 from inside, so that no disturbing light falls into the room containing the audience.

In the drawing affixed to this specification and forming part thereof one embodiment of my invention is shown by way of example. 100

In the drawing

Fig. 1 is a front elevation of the improved apparatus,

Fig. 2 is a plan of the same,

5 Fig. 3 is a detail on a larger scale,

Fig. 4 is a plan of a modified pointer, and

Fig. 5 is an elevation of a device for adjusting the finger or pointer.

Similar parts are indicated by the same 10 letters of reference throughout all the figures of the drawing.

Referring to Figs. 1 and 2 *a* is the music-tape or ribbon which is unwound from the drum *b* and coiled up on the drum *c*. The 15 tape is provided with indications *z* pointing out prominent moments of the film, such as title, scene and so on and with graduations such as *o*, 10, 20 and so on. Above the tape is situated the finger or pointer *d* fixed upon a bushing or sleeve *f* adapted to be moved along a stationary metallic guide-rod *e*. A tail piece *g* of the sleeve *f* rides with a fork *h* upon a resistance *i*, which may be wound in a special manner. 20 With one of the supports *k* of the guide-rod *e* and with the opposite end *m* of the resistance *i* are connected the ends of an electric circuit which directly or indirectly controls the driving motor *y* for the projecting apparatus. 25 In the sleeve *f* is provided an electric circuit breaker or cut-out switch *n*. The electric current passes from the support *k* through the guide-rod *e* to the sleeve *f* and through the circuit breaker *n* to the tail piece *g* and from there through the fork *h* into the resistance *i* which it leaves at the 30 terminal *m*. The circuit can be interrupted by opening the switch *n*.

In order to enable certain adjustments of 35 the finger *d* to be made without affecting at the same time the motor owing to changes in the series resistance *i* the latter is mounted upon a slide *o* adapted to be moved along a dovetailed guide *p* or the like in the base-plate *q* together with the finger *d*.

Another construction for moving the finger *d* above the music-tape without simultaneously affecting the circuit of the projecting apparatus is shown on an enlarged scale 40 in the Figs. 4 and 5. In this case a bar *s* is slidably secured in a guide portion *r* of the sleeve *f* and upon said bar is mounted the finger *d*. The bar is provided with a rack *t* with which engages a pinion *u*, shown 45 in dotted lines in Fig. 5, fixed upon the spindle *w*, also shown in dotted lines, of a knob *x*. By turning the knob *x* by hand the finger *d* may be moved to the right or left, as desired.

60 It will be understood that the details of the construction may be modified in many ways within the ambit of my claims without departing from the spirit of my invention or sacrificing any of its advantages.

What I claim as my invention and desire 65 to secure by Letters Patent is:—

1. In apparatus for obtaining synchronism between the pictures and music in animated picture performances, the combination of a music tape travelling in synchronism with a picture film and having musical notation running longitudinally of the tape, an indicator finger mounted in proximity to the notes on said tape and for adjustment in the reading direction of said notes, a driving motor for said picture film, and means for controlling the speed of said motor controlled by the adjustment of said finger.

2. In apparatus for obtaining synchronism 80 between the pictures and music in animated picture performances, the combination of a music tape travelling in synchronism with a picture film and having musical notation running longitudinally of the tape, an indicator finger mounted in proximity to the notes on said tape and for adjustment in the reading direction of said notes, a driving motor for said picture film, a series resistance in the circuit of said motor, and means 85 on said finger for cutting in or out said resistance upon adjustment of the finger to thereby control the speed of said motor.

3. In apparatus for obtaining synchronism 90 between the pictures and music in animated picture performances, the combination of a music tape travelling in synchronism with a picture film and having musical notation running longitudinally of the tape, an indicator finger mounted in proximity to the notes on said tape and for adjustment in the reading direction of said notes, and means 95 for controlling the speed of movement of the picture film controlled by the adjustment of said finger, the synchronism being brought about by the attendant adjusting the finger upon the note which is being sounded at the moment.

4. An apparatus in accordance with claim 110 2 in combination with means for adjusting said finger along said music tape without varying said resistance.

5. In apparatus for obtaining synchronism 115 between the pictures and music in animated picture performances, the combination of a music tape travelling in synchronism with a picture film and having musical notation running longitudinally of the tape, an indicator finger mounted in proximity to the notes on said tape and for adjustment in the reading direction of said notes, a driving motor for said picture film, a series resistance in the circuit of said motor, and means 120 on said finger for cutting in or out said resistance upon adjustment of the finger to thereby control the speed of said motor, said finger and said resistance being also adjustable as a unit along said music tape.

6. In apparatus for obtaining synchronism between the pictures and the music in animated picture performances, the combination of a music tape travelling in synchronism with a picture film, said tape having musical notation running longitudinally thereof and also marks indicating prominent moments of the film, an indicator finger mounted in proximity to said tape and for adjustment in the reading direction of said musical notation, and means for controlling the speed of movement of the picture film controlled by the adjustment of said finger, said marks facilitating the re-establishment of synchronism of picture and music when the synchronism has been lost.
- In testimony whereof I affix my signature.
- ADOLF BEENEKEN.
